(57) **CLAIM**

The ornamental design for an awning louver, as shown and described.

DESCRIPTION

FIG. 1 is a front, left and bottom perspective view of an awning louver, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The drawings contain symbolic break lines in FIGS. 1 and 4-7. The portions of the article between the break lines forms no part of the claimed design.
